UNITED STATES PATENT OFFICE.

FRED GEORGE SCHWEISTHAL, OF CHICAGO, ILLINOIS, ASSIGNOR TO STEWART-WARNER SPEEDOMETER CORPORATION, OF CHICAGO, ILLINOIS, A CORPORATION OF VIRGINIA.

SPEEDOMETER-MAGNET COMPENSATOR.

Application filed February 12, 1925, Serial No. 3,669. Renewed December 12, 1925.

The purpose of this invention is to provide an improved compensating device for permanent magnets such as those employed in tachometers and speedometers, the compensator being particularly designed and shown for thermostatic operation to make the proper correction in the magnet throughout a range of temperature change. The invention consists in certain features and 5 elements of construction in combination as herein shown and described and as indicated by the claims.

In the drawings:—

Figure 1 is a top plan view of a tachometer magnet with its associated mount and thermostatic compensating device fitted with the improvement embodying this invention.

Figure 2 is a diametral section taken as indicated at line 2—2 on Figure 1.

Figure 3 is a section taken as indicated at line 3—3 on Figure 1.

Figure 4 is a fragmental perspective view for indicating more clearly the relation of the antifriction device to the associated 20 parts.

In tachometers and speedometers employing permanent magnets of annular form it is standard practice to provide temperature compensation for such magnets by overlapping the gap of the magnet with a movable shunt plate which is rendered adjustable by thermostatic means for varying its overlap on the magnet poles and thus varying the portion of the flux which is diverted 30 through the shunt plate. This compensating device is so designed as to maintain the magnetic field outside the magnet at a substantially constant strength notwithstanding the 35 change of permeability which occurs upon 40 change of temperature. A device of this nature is shown in Letters Patent No. 1,155,346, issued October 5, 1915.

When a compensating shunt plate of this character is mounted in actual contact with 45 the face of the magnet it is found that there is some tendency for it to stick to the magnet so as to require considerable force to slide it over the magnet face for shifting its relation to the gap at the poles. This 50 tends to prevent a perfectly continuous compensation as the temperature varies, because it requires the thermostatic device to accumulate the necessary force through a change of several degrees of temperature before it

can initiate movement of the shunt plate. 55 The present invention therefore provides anti-friction means acting to hold the shunt plate out of contact with the face of the magnet and thus permitting it to be shifted much more readily. 60

In the drawings the usual annular form of magnet is shown at 1 with a radial rift or slot at 2 between its poles. The magnet is supported on a mount, 3, usually of die cast non-magnetic metal, filling the center of the annular magnet, 1, and itself secured to the drive shaft, 4. The shunt plate is shown at 5 partially overlapping the gap, 2. Within a central space, 6, in the mount, 3, a curved bi-metallic bar, 7, serves as the 70 thermostatic means for shifting the shunt plate, 5. Said bar is anchored to the mount at one end by a screw, 8, and at the other end is formed with a lug, 9, shown as passing through a fitted aperture in the plate, 5, and riveted over for permanent attachment thereto. 75

In the portion of the mount, 3, which extends between the central opening, 6, and the magnet, 1, a steel ball, 10, is pocketed in a trough or recess, 11, directly below the shunt plate, 5; and the recess, 11, is of such depth that the ball, 10, will just prevent contact between the shunt plate, 5, and the face of the magnet, 1. As the thermostatic bar, 7, shifts the plate, 5, in circumferential direction the ball rolls slightly in the recess, 11, but the range of movement is so limited that the ball is always retained under the plate, 5, for holding it out of contact with the magnet 85 face and preventing it from sticking to the magnet in opposition to the force of the thermostat, 7. 90

I claim:—

1. In a tachometer a permanent magnet 95 and a non-magnetic mounting member by which the magnet is rotatively carried, a compensating shunt plate and means by which said shunt plate is carried by the mounting member for lapping the magnet adjacent its poles, automatic means to move said shunt plate relatively to said magnet poles, and means interposed between the mount and the shunt plate for spacing the shunt plate from the magnet pole, said 100 means being adapted to move freely with the shunt plate at the side in contact therewith. 105

2. In a tachometer a split ring magnet, and a non-magnetic mount upon which it is carried, a compensating device, comprising a shunt plate, also carried by the mount and overlapping the gap between the magnet poles at one face of the latter; and means interposed between the mount and the free end of the compensating member for spacing the shunt plate from the magnet poles, said means being adapted to move freely with the shunt plate at the point of lodgement of the latter thereon.

3. In a tachometer a split ring magnet, a shaft for rotating it about its axis, a non-magnetic mounting member secured to the shaft and centrally disposed in the magnet for carrying the latter, a calibrating member secured to the mount at one end, and at the other end having a compensating shunt plate overlapping one face of the magnet adjacent to its poles; means for moving the shunt plate with respect to the magnet poles, and a rolling member between the mounting member and the shunt plate, dimensioned for spacing the shunt plate from the magnet poles.

4. In a tachometer a split ring magnet, and a shaft rotating the magnet, a non-magnetic mount secured to the shaft and centrally disposed in the magnet, a shunt plate lapping the magnet adjacent to its poles, a thermostatic device secured to the mount and to said shunt plate for moving

the latter circumferentially with respect to the magnet to vary its overlap at the magnet poles, said shunt plate being extended from its connection to the thermostatic device across the non-magnetic mount for lapping the poles, and a rolling spacing member lodged in the mount under the shunt, dimensioned for spacing the shunt plate out of contact with the surface of the magnet.

5. In a tachometer a permanent magnet, a mount by which it is carried, a compensating shunt plate and thermostatic means by which the shunt plate is carried by the magnet mount for movement of the shunt plate relative to the magnet poles, and anti-friction means interposed between the magnet mount and the shunt for holding the shunt plate spaced away from the magnet poles.

6. In a tachometer, a permanent magnet, a non-magnetic mounting member by which the magnet is rotatively carried, a compensating shunt plate, thermostatic means by which said shunt plate is carried by the mounting member lapping the magnet adjacent its poles and for movement of said plate rotatively relative to said poles, and co-operating means between the mounting member and the shunt plate for holding the shunt plate spaced away from contact with the magnet.

FRED GEORGE SCHWEISTHAL.
